UNITED STATES PATENT OFFICE.

EUGENE H. BALLOU, OF PAWTUCKET, RHODE ISLAND.

FILLING DETECTOR.

Application filed May 29, 1925. Serial No. 33,676.

To all whom it may concern:

Be it known that I, EUGENE H. BALLOU, a citizen of the United States, residing at Pawtucket, in the county of Providence and State of Rhode Island, have invented new and useful Improvements in Filling Detectors, of which the following is a specification.

This invention relates to certain new and useful improvements in filling detectors, and the primary object thereof is to provide an electrically operated feeler for effecting operation of the device which removes empty bobbins from the loom and replaces or replenishes same with full bobbins.

A further object of the invention is to provide simple, and economical means for effecting electrical operation of the bobbin removing and replenishing device, efficiently and with certainty.

In the drawings:—

Figure 1, is a top plan view of the invention;

Figure 2 is a section on line 2—2 of Fig. 1; Figure 3 is a side elevation of Fig. 1 and

Figure 4 and Fig. 5 are fragmentary views of two different forms of bobbins employed in connection with the invention.

In proceeding in accordance with the present invention, a bracket 1, is employed, which is bolted at 2 to the frame 3, of the bobbin removing and replenishing device, the latter generally designated 4. The bracket is provided with a slotted guide 5, in which a slide 6, formed of insulating material is movable. The forward end of the slide is provided with a pair of metal points 7, which are mounted in longitudinal bores formed in the slide. The points

7, have rods 8, connected thereto, the rear ends of which rods have metal contacts 9, secured thereto. Springs 10, surround the rods 8, and normally urge the points 7, forwardly of the slide.

The rear end of the slide is cutaway to accommodate the contacts, whereby the upper faces of the contacts 9 project above the upper face of the slide, although same may be flush therewith, if desired.

A spring tensioned rod 12, is slidably carried by a guide 13, at the rear of the bracket 1, and has its forward end connected to the rear end of the slide so as to normally urge the latter outwardly. Adjustable nuts 14, on the rear end of the rod, abut the

guide 13, and control the extent of forward movement of the rod.

An electric coil 15, is mounted on the bracket in opposed relation to an armature 16, the latter having a stem 17, slideable in guide 13, and tensioned by a coil spring 18. An L-shaped finger 19, is carried by the stem 17, and is held thereon by and between nuts 20. A pair of spring fingers 21, are carried by the bracket and have wiping contact with the contacts 9. Wires 22 and 23, lead from any suitable source of electrical supply, not shown, to the coil and fingers 21.

The bobbins A and B are provided with metallic ferrules, preferably copper, which may be either plain as shown at 24, or corrugated as shown at 25. In the instance of the plain ferrule, the bunch must be built on the bobbin to allow sufficient leeway for the shuttle to cross the shed. In the instance of the corrugated ferrule, sufficient yarn, during building or spinning is laid in the dwells of the corrugations to take the place of the bunch.

The rod 12, has an arm 26, rigidly connected thereto adapted to be operated by a withdrawing arm or member 27, of the loom, while the finger 19 is perforated and receives therethrough, a pin 28, which latter operates the bobbin removing and replenishing device 4.

In operation, it will be understood that so long as the bobbin has sufficient layers of yarn thereon to prevent engagement of the points 7, with the copper ferrule of the bobbin, the bobbin removing and replenishing device will be inactive. Upon emptying of the bobbin the contact points 7, will engage the copper ferrule of the bobbin and complete an electrical circuit through the coil 15, energizing the latter and thereby attracting the armature 16. The armature 16 will thus be slid to the right of the drawings, causing its stem 17, to move the finger 19, to the right, thereby actuating the pin 28, and rendering the bobbin removing and replenishing device active, to remove the empty bobbin and supply a fresh bobbin to the loom. Immediately following closing of the circuit, as described, the arm 27 will enter into action and engaging the arm 26, will move the latter and therewith, the insulating slide 6, to the left of the drawings, so as to dispose the contacts 7, 7, in

a position outwardly of the shuttle box, thereby not to interfere with the movement of the fresh filled bobbin to its position in the loom, and upon disengagement of the 5 arm 27, from the arm 26, the spring 30 surrounding rod 12, will restore the parts to normal position as depicted in Figure 1.

Having thus described my invention what I claim as new and desire to secure 10 by Letters Patent is:—

1. In combination with a device for removing and replacing bobbins, and bobbins having metallic ferrules thereon, a slide having spring pressed contacts for engagement 15 with the ferrules, a coil, other contacts on the slide, contact fingers connected to the coil and engageable with said other contacts of the slide, a slideable spring pressed armature for the coil, a finger carried by the 20 armature for operating the bobbin removing and replacing device, and withdrawing means for the slide.

2. In combination with a bobbin removing and replacing device and bobbins having metallic ferrules thereon, a solenoid, a 25 slideable tensioned armature for the solenoid, means connected to the armature and to said bobbin device for actuating the latter, a slide independent of the armature having 30 contacts engageable with the bobbin ferrule and having other contacts, and means electrically connected to the solenoid and having 35 slideable contact with the said other contacts of said slide to complete a circuit through the solenoid upon engagement of the first named contacts of said slide with the bobbin ferrule.

3. In combination with a bobbin removing and replacing device and bobbins having metallic ferrules thereon, a solenoid disposed adjacent and opposite to the ferrules, an armature for the solenoid, means connected to the armature and to said bobbin device for actuating the latter, and means 45 interposed between the armature and fer-

rule and operable independently of the armature for closing a circuit through the solenoid and having contacts engageable with the ferrule.

4. In combination with a bobbin removing 50 and replacing device and bobbins having metallic ferrules thereon, a solenoid disposed adjacent and opposite to the ferrules, an armature for the solenoid, means connected to the armature and to said bobbin device for actuating the latter, means interposed between the armature and ferrule and operable independently of the armature for closing a circuit through the solenoid 55 and having contacts engageable with the ferrule and withdrawing means for the slide to move same away from the bobbin.

5. In combination with a device for removing and replacing bobbins, and bobbins having metallic ferrules thereon, a slide having 60 contacts for engagement with the ferrules, a coil, other contacts on the slide, contact fingers connected to the coil and engageable with said other contacts of the slide, an armature for the coil, means carried by the armature for operating the bobbin removing and replacing device, and withdrawing means for the slide.

6. In combination with bobbins having metallic ferrules, and a bobbin removing 65 and replenishing device, a solenoid disposed adjacent and opposite to the ferrules, an armature at one end of the solenoid, means to connect the armature to said device to actuate the latter, contacts connected to the 70 opposite end of the armature, a slide interposed between the solenoid and ferrules and having contacts engageable with the contacts of the armature and having other contacts engageable with the bobbin ferrule, 75 and a tensioned withdrawal device for the slide connected thereto.

In testimony whereof I have signed my name to this specification.

EUGENE H. BALLOU.
